UNITED STATES PATENT OFFICE.

FRITZ VOGELSANG, OF CHARLOTTENBURG, NEAR BERLIN, GERMANY.

DOOR-LOCK.

1,312,219.

Specification of Letters Patent. Patented Aug. 5, 1919.

Application filed March 16, 1915. Serial No. 14,756.

To all whom it may concern:

Be it known that I, FRITZ VOGELSANG, merchant, of Charlottenburg, near Berlin, Germany, subject of the German Emperor, 5 residing at Charlottenburg, near Berlin, Germany, have invented certain new and useful Improvements in Door-Locks, of which the following is a specification.

The invention relates to a door lock which 10 permits of easily opening the door with the right key but affords a double check against the unauthorized opening of the said door, without requiring special manipulation when shutting the door, as both safety members (door lock and latch) assume the locking position automatically when shutting the door.

The accompanying drawings illustrate, by 15 way of example, a constructional form of the invention.

Figure 1 shows the lock casing with the safety bolt mounted pivotally therein, viewed from the inner side of the door.

Fig. 2 shows the door closed and locked. 20 Fig. 3 is a view similar to Fig. 2, the door lock being opened from within but the safety bolt not yet fully withdrawn.

Fig. 4 is a similar view to Fig. 3, the lock being opened from without by means of a 25 key, the safety bolt being withdrawn.

Fig. 5 is a section taken on line I—I of Fig. 2.

Fig. 6 is a section taken on line II—II of Fig. 4, and

Fig. 7 is a view of the removed lock casing cover.

Fig. 8 is a part plan and part sectional view of the safety-bolt and its mountings, and

Fig. 9 is an elevation of the same parts.

The opening part a' of the door is provided with the lock casing b , which has associated with it the safety bolt c . The latter which is mounted to have both a vertical and a horizontal swinging movement with relation to its pivot c' , has a head c' which is adapted to slide, when the door closes on the inclined face d^3 of the box-like keeper plate or casing d secured to the stationary part a^2 of the door or to the frame thereof and drops into the recess d' in the keeper, and when opening the door it can move in the slot d^2 formed in the said keeper, to the extent limited by the said slot.

Referring to Figs. 8 and 9, for the pivotal mountings of the safety-bolt c , it will be

noted that a head c^5 extends through the front of the casing b and has its shank rotatably carried in the sleeve c^6 which may be formed as a part of said casing. Keyed 60 on the inner end of the shank of the head c^5 , so as to rotate therewith, as best shown in Fig. 9, is a plate c^4 , whose functions will hereinafter appear. A screw c^2 is threaded into the inner end of the shank, and serves 65 to hold the plate c^4 in place, the latter, together with the screw, also acting to lock the head c^5 in position. The head c^5 is laterally slotted to form a recess c^7 inclosed by the upper and lower halves of said head, 70 and in said recess is pivoted the arm or safety-bolt c , said bolt having, adjacent its pivotal point, a cam-surface c^8 , against which a pin c^9 operates. The pin c^9 stands under pressure of a spring c^{10} which is 75 inclosed in the shank of the head and normally tends to push the arm c away from the lock. The screw c^2 acts as a retainer for the spring c^{10} . It will thus be seen that the safety bolt c is capable of a vertical and horizontal piv- 80 otal movement.

The lock casing b is provided with a latch-bolt e and with an auxiliary bolt f externally of similar shape. The latch bolt e which on shutting the door enters a corresponding aperture formed in the keeper d (Fig. 2) is mounted on a rod e' guided in a bearing b' and at its free end is provided with a projection e^3 . Between the latch bolt e and the bearing b' , a coiled spring e^2 is 90 provided surrounding the rod e' , said spring tending to hold the latch bolt in its closed position.

The auxiliary bolt f is mounted on a rod f' which is guided in the bearing b^2 parallel 95 to the rod e' . A spring f^2 surrounding this rod, forces the bolt f in an outward direction, said bolt f coöperating with a locking lever g provided in the lock casing and rotatable about the pivot g^4 . This locking 100 lever g is under the influence of the spring g^5 which is secured thereto and bears on the bearing b' , said spring tending to push the locking nose g' provided on the front arm of the lever g into the path of the latch bolt 105 e . The action of the spring g^5 is opposed by the action of the auxiliary bolt f which is connected by the cross-member f^3 with the rod e' of the latch bolt e , said member having an aperture through which rod e' extends; and in the position shown in Fig. 1, 110 that is to say when the auxiliary bolt is in

its outermost position, this cross-member f^3 engages underneath the nose g' and pushes the same out of the path of the latch bolt e .

When the door is closed, the latch bolt e and the auxiliary bolt f are pressed inwardly by the wall of the casing d sliding on their oblique surfaces. As in this case the cross-member f^3 bears closely against the latch bolt e , the inward displacement of the latch bolt is not interfered with by the locking nose g' which contacts idly with the cross-member and the upper surface of the latch bolt. As soon as the door is completely closed, the latch bolt shoots forward under the action of its spring e^2 into the corresponding aperture formed in the keeper casing d . The auxiliary bolt f , however, owing to the fact that it has not a corresponding aperture in the wall of the casing d to shoot into, is retained in its inner position so that the locking nose g' places itself, under the action of its spring g^5 , in front of the latch bolt e and locks the same. In this manner the latch bolt is automatically locked when shutting the door so that it is impossible to push the same back by means of an implement forced in the chink of the door. At the same time the lock bolt has automatically re-assumed its locking position in the above-described manner (Fig. 2).

The opening of the lock from within is effected by means of the handle h (Fig. 5) secured rotatably on the casing d , and provided with the plate i formed with the two arms i' , i^3 . The arm i' limits by contact with the lock casing, the rotation of the handle h in one direction. When the handle h is rotated in the other direction indicated by the arrow (Fig. 2), the arm i' pushes by means of its bent end i^4 engaging in a recess g^2 formed in the locking lever g , the latter in a downward direction against the action of the spring g^5 so that its nose g' is removed from the path of the latch bolt e . A pin i^2 mounted on the arm i' presses then on the projection e^3 provided on the latch bolt rod e' and thereby withdraws the released latch bolt from the casing d against the action of the spring e^2 (Fig. 3).

The door can now be opened to an extent determined by the head c' of the safety bolt c , sliding in the slot d^2 formed in the keeper casing d , during which time the safety bolt c is swung or rocked horizontally relatively to its pivot C^2 . Should it be desired to open the door completely, the safety bolt c is raised with a finger when the door is closed so that the head c' of the said bolt is removed from the recess d' formed in the casing d and the door can now be fully opened.

In order to open the door from without, only a single key is necessary. Preferably a safety lock is used of the type in which, after setting the tumblers, a cylinder can be

rotated by the key. The lock cylinder h (Fig. 7) rotatably secured to the cover 1 of the casing b , is provided with two wings k' , k^2 arranged at right angles to each other (Figs. 4 and 7) one of which, k' , releases, 70 when rotating the said cylinder, the latch bolt e by acting on the pin i^2 and withdraws this bolt while the other k^2 releases the safety bolt c . The latter is released owing to the fact that the wing k^2 bears downwardly on a bent part c^3 of a plate c^4 connected with the pivot c^2 of the safety bolt, thereby rocking said bolt upwardly about said pivot. In Fig. 4 the parts have been represented in the position which they assume when by means of a key the released latch bolt is completely withdrawn and the safety bolt is being raised. In this position of the parts, the door can be opened to its fullest extent. 75

In the lock casing b a plate m is provided which by means of the knob m^2 can be displaced from within and which is formed with a lug or finger m' adapted to engage in a corresponding groove e^4 in the latch bolt rod e' when said plate is in its locking position (Fig. 2). This prevents the release and withdrawal of the latch bolt as well as the release of the safety bolt because the rotation of the cylinder h is prevented by the abutment of the wing k' or the pin i^2 on the projection e^3 of the stationary or fixed latch bolt rod e' . The door cannot be opened from without even with the right key. 80

Of essential importance in this invention, 100 is the coöperation of the safety bolt with the latch bolt which is automatically locked when shutting the door. The safety bolt may, in this connection, have a different shape. Even the construction of the safety 105 lock for opening the door from without, is not of essential importance and any safety lock may be used for this purpose.

Having now particularly described and ascertained the nature of my said invention 110 and in what manner the same is to be performed, I declare that what I claim is:

1. In a door-lock, the combination of a locking-mechanism, a keeper, a safety-bolt mounted on said locking-mechanism and 115 having a vertical movement to disengage said keeper and a horizontal movement to permit movement of the lock relative to said keeper, means interposed between said safety-bolt and said locking-mechanism to release said safety-bolt, said locking means including a latch-bolt, and means to positively lock the latch-bolt when the door is completely closed.

2. In a door-lock, the combination, with 125 a locking mechanism, a casing therefor, and a keeper; of a safety bolt for engagement with said keeper having a pivotal mounting within the casing to swing vertically to disengage said keeper and also to swing later- 130

ally to permit movement of the locking mechanism and its casing relative to said keeper; a releasing member within said casing operable upon said safety bolt to positively effect its vertical, disengaging movement; and means for actuating said releasing member.

3. In a door-lock, the combination, with a locking mechanism, a casing therefor, and a keeper; of a safety bolt for engagement with said keeper having a pivotal mounting within the casing to swing vertically to disengage said keeper and also to swing horizontally to permit movement of the locking mechanism and its casing relative to said keeper; a releasing member within said casing operable upon said safety bolt to positively effect its vertical, disengaging movement; and key-operated means for actuating said releasing member.

4. In a door-lock, the combination, with a locking mechanism, a casing therefor, and a keeper; of a safety bolt mounted within said casing and having a portion projecting exteriorly thereof for engagement with said keeper; a depressible plate within said casing connected directly to said safety bolt to positively move the same out of engagement with said keeper when said plate is depressed; and actuating means for said plate.

5. In a door-lock, the combination, with a keeper; of a locking mechanism embodying a rotatable, key-operated cylinder; a casing for the locking mechanism; a safety bolt mounted within said casing and having a portion projecting exteriorly thereof for engagement with said keeper; a releasing member within said casing operable upon said safety bolt to positively move the same out of engagement with said keeper; and means carried by said cylinder for actuating said releasing member.

6. In a door-lock, the combination, with a locking mechanism, a casing therefor, and a keeper; of a safety bolt mounted within said casing and having a portion projecting exteriorly thereof for engagement with said keeper; a releasing member mounted to turn within the casing and operable upon said safety bolt when so turned to positively move it out of engagement with said keeper, said member being provided with a bent

part; and key-operated means operable upon said bent part to positively actuate said releasing member.

55

7. In a door-lock, the combination, with a keeper; of a locking mechanism embodying a rotatable, key-operated cylinder; a casing for the locking mechanism; a safety bolt mounted within said casing and having a portion projecting exteriorly thereof for engagement with said keeper; a releasing member mounted to turn within said casing and operable upon said safety bolt when so turned to positively move it out of engagement with said keeper and provided with a bent part; and means operated by the rotation of said cylinder adapted to engage said bent part, so as to turn said releasing member.

70

8. In a door-lock, the combination, with a keeper; of a locking mechanism embodying a rotatable, key-operated cylinder; a casing for the locking mechanism; a safety bolt mounted within said casing and having a portion projecting exteriorly thereof for engagement with said keeper; a releasing member within said casing operable upon said safety bolt to positively disengage the same from said keeper and provided with a bent part; and an arm connected to said cylinder and adapted to engage said bent part, so as to actuate said releasing member.

75

9. In a door-lock, the combination, with a keeper; of a locking mechanism embodying a rotatable, key-operated cylinder; a casing for the locking mechanism; a safety bolt having a pivotal mounting within the casing to swing vertically to disengage said keeper and also to swing horizontally to permit movement of the locking mechanism and its casing relative to said keeper; a releasing member within said casing operable upon said safety bolt to positively effect its vertical, disengaging movement; and means operated by the rotation of said cylinder for actuating said releasing member.
